(57) **CLAIM**

The ornamental design for a hinged solar collector for light, as shown and described.

DESCRIPTION

FIG. 1 is a perspective view of the hinged solar collector for light according to the present invention.

FIG. 2 is a front view of the hinged solar collector for light according to the present invention.

FIG. 3 is a right side view of the hinged solar collector for light according to the present invention.

FIG. 4 is a left side view of the hinged solar collector for light according to the present invention.

FIG. 5 is a rear view of the hinged solar collector for light according to the present invention.

FIG. 6 is a top view of the hinged solar collector for light according to the present invention; and,

FIG. 7 is a bottom view of the hinged solar collector for light according to the present invention.

The broken lines are for illustrative purposes only and form no part of the claimed invention.
